UNITED STATES PATENT OFFICE.

JAMES C. BADGER, OF CONCORD, NEW HAMPSHIRE.

DESIGN FOR A SPOON.

SPECIFICATION forming part of Design No. 21,777, dated August 16, 1892.

Application filed June 10, 1892. Serial No. 436,271. Term of patent 3½ years.

To all whom it may concern:

Be it known that I, JAMES C. BADGER, a citizen of the United States, residing at Concord, in the county of Merrimac and State of New Hampshire, have invented and produced a new and original Design for a Spoon, of which the following is a specification, reference being had to the accompanying drawing, forming part thereof.

- 10 The drawing represents a spoon having my design in the concaved side of its bowl, this single view being all that is deemed necessary to illustrate the design, the leading feature of which consists in a spoon or similar article 15 having in the bowl thereof the representation of a stone arch, the outline of which will be sufficiently small to admit of the representation of a few trees upon either side, somewhat in the background, and the whole picture falls 20 within a scalloped outline, other features of my design being specified as follows:

The arch A, at either side of the opening B, may be provided with a vase C or its equivalent, and plants or flowers may be represented

protruding from it. The two front corners D 25 of the arch A will be ornamented near their top or at a point about two-thirds the distance from the ground-line to the cornice of said arch with carved tablets E, (one for each corner,) and the top of the arch above the cornice F terminates in successive layers of stone G, diminishing in length, the upper one H being quite short. Another feature of my design are the tablets J, extending from each side of the arch A to a column K, rising vertically and mounting a spherical stone L, as seen. The foreground represents a sidewalk, its curbing, and a portion of a street.

Having described my design, what I claim is—

The design for a spoon, substantially as shown and described.

In testimony whereof I affix my signature in presence of two witnesses.

JAMES C. BADGER.
